UNITED STATES PATENT OFFICE.

SETH K. DEVEREUX, OF CASTINE, MAINE.

JEWEL-STAND.

SPECIFICATION forming part of Letters Patent No. 230,756, dated August 3, 1880.

Application filed March 29, 1880. (No model.)

To all whom it may concern:

Be it known that I, SETH K. DEVEREUX, of Castine, in the county of Hancock and State of Maine, have invented a new and Improved 5 Jewel-Stand, of which the following is a specification.

This invention consists of a round or oval jewel-stand, principally for ladies' use, having a concave or hollowed-out top and provided 10 with four drawers of the peculiar shape below set forth.

Two opposite drawers have parallel, or nearly parallel, sides, and are convex at their inner ends; and the other two have sides which are 15 parallel, or nearly so, for a portion of the distance back, ends at right angles to the parallel portions of the sides, and concave portions in each side, the curves being such as to allow the convex portions of the first two drawers to fit 20 into the concave portions of the last two drawers. Thus the space in the central portion of the stand is utilized.

In the accompanying drawings, in which similar letters of reference indicate like parts,

25 Figure 1 is an elevation of a jewel-stand embodying my improvements. Fig. 2 is a horizontal section on line $x-x$, Fig. 1. Fig. 3 is a vertical section of the upper portion on line $y-y$, Fig. 2.

30 a and a' are the upper and lower pieces of wood in the top of the stand, the former being provided with the concavity a'' for the accommodation of cards, jewelry, &c.

b shows the portions of the table separating 35 the outer portions of the drawers.

c are opposite drawers. The fronts of the 40 drawers are straight or conform to the shape of the stand. The sides c' are parallel, or nearly so. The backs c'' are curved, thus producing convex inner ends.

d are the other two opposite drawers. The fronts are similar to those in the drawers c . The portions d' of the sides are parallel, or nearly so. The rear ends, d'' , are straight and at right angles to the portions d' , and at d''' 45 the sides are curved inwardly, making two concave portions in each drawer d .

It will be seen that the convex portions c'' in the drawers c exactly fit into the concave portions d''' in the drawers d , each convex end 50 filling two concave sides. The ends d'' of the drawers meet, or nearly meet, and every inch of space in the center of the interior of the table is utilized.

The drawers are provided with padded linings e for the accommodation of the jewelry. 55

The stand may be circular or oval, and may be ornamented in any desired manner and made of any size.

Having thus fully described my improvement, I do not claim that non-rectangular drawers are novel, nor that drawers provided with no inner separating-partitions are new; 60 but

What I claim, and desire to secure by Letters Patent, is— 65

The herein-described circular or oval jewel-stand, provided with the top a and the two sets of drawers c and d , of the shapes shown, and arranged, as described, to allow the 70 convex ends of the two drawers c to fit into the concave sides of the other two drawers, d , for the purpose set forth.

SETH K. DEVEREUX.
